United States Patent [19]

Carr

[11] Des. 271,393

[45]  Nov. 15, 1983

[54] TELEPHONE HANDSET

[75] Inventor: Peter B. Carr, Harpenden, England

[73] Assignee: International Standard Electric Corporation, New York, N.Y.

[] Term: 14 Years

[21] Appl. No.: 239,735

[22] Filed: Mar. 2, 1981

[30] Foreign Application Priority Data

Aug. 28, 1980 [GB] United Kingdom 996341

[51] Int. Cl. ..... D14—03

[52] U.S. Cl. D14/63; D14/64

[58] Field of Search D14/63, 64, 53, 58,
D14/56; 179/100 R, 100 D, 100 C, 103, 178,
179, 146

[56] References Cited

U.S. PATENT DOCUMENTS

D. 209,910 1/1968 Tyson D14/63

D. 227,782	7/1973	Hazell et al.	D14/63
D. 229,837	1/1974	Genaro et al.	D14/63
D. 236,627	9/1975	Henshew et al.	D14/63
D. 245,602	8/1977	Genaro et al.	D14/63
D. 256,583	8/1980	Marshall	D14/63
D. 263,048	2/1982	Genaro et al.	D14/63
D. 266,561	10/1982	Bee et al.	D14/63
3,515,816	6/1970	Laing	179/100 R
3,558,831	1/1977	Prescott	179/100 R

Primary Examiner—Bernard Ansher

Attorney, Agent, or Firm—John T. O'Halloran; Peter R. Ruzek

[57] CLAIM

The ornamental design for a telephone handset, as shown.

DESCRIPTION

FIG. 1 is a perspective view from above and one side of the telephone handset;

FIG. 2 is a view of the far end of the telephone handset;

FIG. 3 is a side view from one side the opposite side is similar of the telephone handset; and

FIG. 4 is a top plan view of the telephone handset.

FIG. 1

FIG. 2

FIG. 3

FIG. 4